DESIGN FOR A GLIDER

William I. Smith, Goshen, Ind., assignor to The Hetrick Manufacturing Company, Toledo, Ohio, a corporation of Ohio

Application January 4, 1941, Serial No. 97,813

Term of patent 7 years

To all whom it may concern:

Be it known that I, William I. Smith, a citizen of the United States and a resident of Goshen, Elkhart County, Indiana, have invented a new, original, and ornamental Design for Glider, of which the following is a specification, reference being had to the accompanying drawing, forming a part thereof.

In the drawing, the figure is a perspective view of a glider, showing my new design.

The characteristic features of my design reside in the portions of the glider shown in full lines in the drawing and particularly the upright end plate members in their relation to and association with the upright supporting members.

I claim:

The ornamental design for a glider, as shown and described.

WILLIAM I. SMITH.
